P. W. BRESNAHAN

TRAIL SIGN

Filed March 14, 1925

INVENTOR.
PATRICK W. BRESNAHAN.
BY HIS ATTORNEYS.

William Reily Williamson

UNITED STATES PATENT OFFICE.

PATRICK W. BRESNAHAN, OF DE GRAFF, MINNESOTA.

DESIGN FOR A TRAIL SIGN.

Application filed March 14, 1925. Serial No. 12,723. Term of patent 7 years.

To all whom it may concern:

Be it known that I, PATRICK W. BRESNAHAN, a citizen of the United States, residing at De Graff, in the county of Swift and State of Minnesota, have invented a new, original, and ornamental Design for a Trail Sign, of which the following is a specification, reference being had to the accompanying drawing, forming part thereof.

The drawing shows a view in front elevation of my new design.

What I claim is:—

The ornamental design for a trail sign, as shown.

PATRICK W. BRESNAHAN.
